UNITED STATES PATENT OFFICE

138,291

DESIGN FOR A PUPPET TOY

Robert K. Ostrander, South Orange, N. J., assignor to Badger Cut Outs, Inc., Maspeth, Long Island, N. Y., a corporation of New York

Application November 15, 1943, Serial No. 111,697

Term of patent 14 years

(Cl. D34—15)

To all whom it may concern:

Be it known that I, Robert K. Ostrander, a citizen of the United States, residing in South Orange, in the county of Essex and State of New Jersey, have invented a new, original, and ornamental Design for a Puppet Toy, of which the following is a specification, reference being had to the accompanying drawing, forming part thereof.

The dominant feature of the design is shown in full lines in the drawing.

I claim:

The ornamental design for a puppet toy, as shown and described.

ROBERT K. OSTRANDER.
